AIR AND OIL FEEDING PUMP

Filed July 21, 1928

UNITED STATES PATENT OFFICE

WILLIAM HENRY DAVENPORT BROUSE, OF TORONTO, ONTARIO, CANADA

AIR AND OIL FEEDING PUMP

Application filed July 21, 1928. Serial No. 294,531.

The principal objects of the invention are, to provide a pump particularly adaptable for furnishing a pressure supply of air and oil to an atomizer for combustion purposes though the pump is equally adaptable for other high speed pressure requirements.

The principal feature of the invention consists in the novel construction and arrangement of parts, whereby the compressor element arranged within a closed pressure chamber is adapted to take in a measured quantity of air and oil and discharge same into the chamber under a common pressure and a valve operated by the compressor rotor co-operates with oil and air passages to conduct supplies of oil and air to the compressing cylinder.

In the drawing, Figure 1 is a vertical mid-sectional view of the pump taken through the axis of the rotor.

Figure 2 is an elevational view of the face of the cap for closing the end of the pump casing and which supports the pumping element.

Figure 3 is a perspective view of the pump rotor.

Figure 4 is a perspective detail of the oscillating valve.

Figure 5 is an elevational section through the rotor and rotor valves showing the position of the valve and rotor at the commencement of the suction stroke with the oil port connected with the rotor cylinder.

Figure 6 is a view similar to Figure 5 showing the rotor in the mid-stroke position.

Figure 7 is a view similar to Figures 5 and 6 showing the position of the ports at the end of the discharge stroke with the air intake open to the cylinder.

In the construction herein illustrated the pump casing 1 is of rectangular form having its open side closed by the cap 2 which is secured thereto in a pressure tight joint by the screws 3.

The cap 2 is provided with a horizontal journal orifice 4 in which the shaft 5 of the rotor 6 is supported.

A block 7 is secured to the inner face of the cap 2 by screws extending therethrough into the holes 8 in the cap and said block is

formed with a cylinder chamber 9 and a cylindrical valve chamber 10.

These chambers are connected by a communicating opening 11.

A cover plate 12 closes the inner side of the cylinder and valve chambers and is provided with a journal bearing 13 supporting the hollow inner end 14 of the rotor shaft.

The shaft 5 has an eccentric portion 15 forming part thereof which fits within the cylindrical axial orifice 16 in the rotor 6 and said eccentric is formed with a peripheral slot 17 communicating with a passage 18 which extends in axial alignment with the shaft and as shown in Figure 1 register with an axial opening in the journal 13.

The slot 17 communicates with a port 19 arranged in the rotor at the bottom side adjacent to the radial vane 20.

The vane 20 of the rotor extends through the opening 11 into the slot 21 in the cylindrical valve 22 arranged in the chamber 10 and causes the valve to oscillate in said chamber as the rotor is carried around in its oscillating movement in the cylinder. This vane 75 is preferably formed with a step 23, as illustrated in Figures 1 and 3 and holes 24 and 25 extend lengthwise of the vane in the respective portions thereof leading from the bottom end to a point immediately adjacent to the cylindrical body of the rotor and said holes extend laterally to the side of the vane opposite from which the port 19 is disposed.

A port 26 in the cover plate 12 communicates with the slot in the valve 22 and this port is connected by an elbow pipe 27 with a passage 28 extending through the cover plate 12 and the bottom of the block 7 and the cap 2 communicating with a laterally extending passage 29 shown in dotted lines in Figure 2 which connects with an oil supply.

The passage 28 is provided with a port 30 leading into the valve chamber 10 at the bottom of the valve and said port is adapted to register with a passage 31 in the valve which is arranged substantially parallel with the axial slot 21, the upper end of said passage 31 communicating with the opening 11 in the cylinder chamber.

An air passage 32 in the cap shown in 100

dotted lines in Figure 2 communicates with a port 33 which is adapted to register with a passage 34 in the valve 22, the upper end of which passage is adapted to communicate with the opening 11 between the cylinder chamber and the valve chamber and is cut off by the wall of the block 7 as the rotor swings the valve in its bearing.

A pipe 35, the lower end of which extends into the lower portion of the chamber, enclosed by the pump casing 1 communicates with a port 36 in the cover plate 12 and leads to a lubricating channel 37 arranged in the rotor 6 at one end of the rotary eccentric 15.

An annular channel 38 surrounds the shaft 5 within the cap 2 to pick up lubricating oil that is forced out along the shaft and the oil flows through a duct 39 and is returned by gravity either to the interior of the casing 1 or to an oil sump 41 in the base.

An oil overflow duct 40 is arranged in the side wall of the pump casing 1 about midway of its height and communicates with the oil sump 41 in the base supporting the pump so that the oil supply cannot entirely fill the interior of the casing 1. A relief valve 40' is arranged in the duct 40.

An oil pipe 42 leads from the lower end of the casing 1 upwardly to a chamber 43 in the top side which communicates with an oil supply pipe 44 and an air pipe 45 leads from the top of the casing 1.

In the operation of this pump the rotation of the shaft 5 rotates the eccentric within the cylindrical portion of the rotor 6 and moves said rotor around the cylinder wall maintaining a portion of its surface in a semi-rolling contact therewith which is sealed by a film of oil.

When the rotor is in the position illustrated in Figure 5 and travelling in the direction indicated by arrow the upward movement creates a suction through the oil channel in the valve and the oil channel in the vane of the rotor, and oil is drawn up into the cylinder through both channels which communicate with the oil feed.

As the valve is rocked in its bearing the oil channel through the valve is closed from communication with the oil duct in the block 7 but oil is drawn into the axial slot in the valve.

The continued movement of the rotor around the cylinder wall swings the air channel clear of the wall of the valve chamber at the opening 11 and air is drawn in.

On the compression side of the rotor vane the oil and air previously drawn into the cylinder is compressed to flow through the port in the rotor and the port and passage in the eccentric after it has been compressed to a pressure higher than the pressure in the main pump casing, and the oil and air are thus forced out through the central passage 18 into the chamber of the main pump casing

so that pressure is built up therein and it will be seen that both the air and oil will be under equal pressure within the pump casing.

As previously described, a pipe 35 extends between the bottom of the casing interior to the passage 36 and annular passage 37 in the rotor. Thus the oil under pressure within the casing is forced up the pipe 35 and fed to the eccentric and as the pressure is external to the channel or passage 37 the oil will be forced between the bearing surfaces of the eccentric and rotor, thoroughly lubricating same.

The overflow passage 40 prevents the rising of the oil past a predetermined level, consequently there will always be a considerable volume of air and oil to be fed from the casing. This is regulated by the relief valve 40'.

The pump is extremely simple. It has very few parts and these operate with the simplest kind of motion, and is capable of being operated at high speeds to produce high pressures which are very useful in the atomization and burning of oil.

The pump while particularly adapted for this service may be used for other purposes such as for refrigeration or it may be used entirely as an air pump, being sealed and lubricated with oil, which of course, under those circumstances will be retained at a lower level in the casing 1.

What I claim as my invention is:—

1. The combination with a pump having a cylinder an eccentrically operating rotor in said cylinder and an oscillating valve operated by the movement of said rotor, of a casing enclosing said pump and adapted to receive the discharge pressure, and means for feeding oil and air separately through said oscillating valve to said pump cylinder to be discharged therefrom into said casing.

2. A pump having a cylinder, an eccentric operating in said cylinder, a rotor mounted on said eccentric, a valve operated by the movement of the rotor having separate oil and air passages therethrough leading to the interior of said cylinder, oil and air passages arranged in the pump casing adapted to communicate with the separate oil and air passages in said valve, said valve passages directing oil and air into the pump cylinder, a discharge passage for said oil and air through the rotor, and a casing enclosing the pump and receiving the discharge from the passage in said rotor.

3. A pump having a cylinder chamber and a communicating valve chamber, an oscillating valve arranged in the valve chamber having separate oil and air passages therethrough leading to the intake side of said cylinder, separate oil and air passages in the pump casing leading to said passages in said valve for conducting oil and air separately thereto, a shaft extending through the pump

cylinder and having an eccentric, a cylindrical rotor sleeve mounted on said eccentric and engaging the wall of the cylinder and having a radial vane extending into said 5 valve to oscillate the same, a port in the rotor on the pressure side of said cylinder, a passage through the eccentric adapted to communicate with the port in said rotor, and a casing enclosing said pump and receiving 10 the discharge therefrom.

4. A pump having a cylinder chamber and a communicating cylindrical valve chamber, a shaft having an eccentric disposed within said cylinder chamber, a longitudinal passage 15 in said shaft opening through one end thereof, a port in the periphery of the eccentric communicating with said passage in the shaft, a rotor mounted on the eccentric in said cylinder chamber and having a port 20 adapted to communicate with the port in said eccentric, a radial vane extending from said rotor into said valve chamber, a cylindrical valve having a diametrically arranged slot receiving the vane of said rotor, an oil passage 25 through said valve communicating with the cylinder chamber at one end, a port in the pump casing adapted to communicate with the oil passage in said valve at a definite period in its oscillating movement, an oil 30 conducting passage leading to said port, an air passage in said valve communicating with the cylinder and adapted to be closed by the cylinder wall at a definite period in the oscillation of the valve, an air supply passage in 35 said pump casing communicating with the air passage in the valve, and a casing enclosing said pump casing and adapted to receive the discharge therefrom.

5. A pump casing having a cylinder chamber and a communicating valve chamber, a shaft extending through said cylinder chamber having an eccentric thereon, a rotor mounted on said eccentric, a discharge passage 40 extending through said eccentric and shaft, a valve in said valve chamber, said valve having a slot, a radial vane extending from said rotor into the slot in said valve, an oil duct in the pump casing communicating with the valve slot in which said vane operates, an oil passage 45 extending through said vane and communicating with the cylinder chamber, an oil passage extending through the valve communicating with the cylinder chamber and adapted to register on the oscillations of the valve with the duct in the casing, an air passage in the valve communicating with an air passage in the pump casing and leading to the cylinder and controlled by the cylinder wall, and a casing surrounding 50 said pump casing and enclosing an oil and air chamber therein.

6. A pump, comprising a closed casing, a shaft journalled in one side of said casing and extending thereinto and having an opening 55 leading inwardly from its inner end and

also having an eccentric and a port opening through the periphery of said eccentric, a block having a cylinder chamber therein secured to the inner wall of said casing and encircling said eccentric and having a valve chamber communicating with the cylinder chamber, a rotor mounted on said eccentric and engaging the wall of the cylinder chamber in sealing contact and having a radial vane extending into the valve chamber, a valve 70 oscillatively arranged in the valve chamber and having a radial slot into which said vane extends, a cover plate closing said cylinder and valve chamber, an oil duct leading to the cylinder chamber through said cover plate and extending downwardly to the lower portion of said casing, intake passages arranged in said casing directing air and oil to the pump, and passages in the valve directing oil and air to the cylinder. 75

7. The combination with a pump having a cylinder, an eccentrically operating rotor in said cylinder, an oscillating valve, said rotor having a vane extending radially therefrom operatively engaging said valve to oscillate the same and separating the inlet side of said cylinder from the discharge side, of a passage in said vane opening directly into the cylinder on the intake side thereof, means for conducting oil to the passage in said vane, and means for conducting air to the intake side of said cylinder separate from said oil. 80

8. The combination with a pump having a cylinder, an eccentrically operating rotor in said cylinder, and an oscillating valve operated by the movement of said rotor, of a casing enclosing said pump and adapted to receive the discharge pressure, an oil passage in said valve for conducting oil to said cylinder, an air passage in said valve separated from said oil passage for conducting air to said cylinder, and a single passage in the shaft of said rotor adapted to conduct the oil and air from said cylinder into the interior of said casing. 100 105

9. The combination with a pump having a cylinder, a rotor eccentrically mounted in said cylinder, an oscillatable valve having a diametrically disposed slot therein, and a vane extending radially from said rotor into said valve slot, of an oil passage conducting oil to the slot in said valve at a point intermediate of its length said passage being opened and closed by said vane in its reciprocating movement within the slot, said vane having passages therein connecting said slot with the interior of the cylinder for conducting oil therebetween, and means controlled by said valve for conducting air to the cylinder. 110 115 120

10. A pump having a cylinder, a rotor eccentrically operating in said cylinder, a valve movable relative to said rotor and operated by direct connection with the rotor and by its movements relative thereto controlling the 125 130

intake of oil and air to said cylinder, a drive shaft, an eccentric on said drive shaft within the rotor and by its rotation effecting the eccentric operation of said rotor, said eccentric controlling the discharge of oil and air from the cylinder, and means receiving the discharged oil and air.

11. A pump having a cylinder, an eccentric operating in said cylinder, a rotor encircling said eccentric and displaced thereby in said cylinder, a valve for separately controlling the intake of oil and air into said cylinder, means forming a sliding and oscillating operating connection between said rotor and valve to control the latter said eccentric and rotor co-operating to control the discharge of oil and air from said cylinder.
